UNITED STATES PATENT OFFICE.

THOMAS M. COBB, OF GRAND RAPIDS, MICHIGAN.

BEE-HIVE.

SPECIFICATION forming part of Letters Patent No. 388,761, dated August 28, 1888.

Application filed April 16, 1888. Serial No. 270,741. (No model.)

To all whom it may concern:

Be it known that I, THOMAS M. COBB, a citizen of the United States, residing at Grand Rapids, in the county of Kent and State of Michigan, have invented certain new and useful Improvements in Bee-Hives; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

This invention relates to certain new and useful improvements in bee-hives; and it relates more particularly to the means of securing together the frames that are provided for holding the surplus-honey sections or cases; and the novelty resides in the peculiar combinations and in the novel construction, arrangement, and adaptation of parts, all as more fully hereinafter described, shown in the drawings, and then particularly pointed out in the appended claims.

The invention is clearly illustrated in the accompanying drawings, which, with the letters of reference marked thereon, form a part of this specification, and in which—

Figure 1 is a side view of the surplus-honey chamber of a bee-hive, consisting of a series of detachable frames for holding the honey sections or cases. Fig. 2 is a section on line $x-x$ of Fig. 1. Fig. 3 is a perspective view of one of the keepers removed. Fig. 4 is a plan view of the surplus-honey chamber; and Fig. 5 is a detail perspective view upon an enlarged scale, showing the frames separated, but in their relative positions.

Reference now being had to the details of the drawings by letter, A A² designate opposite sides of the surplus-honey chamber of a bee-hive, and a a' represent the detachable frames intended for holding the surplus-honey sections.

Each of the frames a is provided with a strip, B, on its outer face, said strip extending upon each side beyond the edge of the frame to which it is attached a sufficient distance to contact with the edge of the next adjacent strip B when the intermediate frames, a', shall have been inserted and these several frames

have been drawn together into position for locking.

It will be observed that in arranging the frames the frames a and a' alternate, and that each alternate frame a' is provided upon its outer face with two staples or hooks, C, which are extended horizontally, one upon each side, beyond the edges of the frame a', and that they are received within suitable slots or recesses, g, formed within the flanged portion of the pieces B upon the adjacent frames. The flanged or overlapping portions of the pieces B are each formed upon their outer face with a channel, d, slightly undercut, as shown, and in this channel is designed to rest the keeper D, formed preferably of wire, with a thumb-piece, e, by which it is handled, and is also bent into the form shown, forming the cam-surface f, which is designed to engage the hook or staple C, as shown in Fig. 1, to draw the frames together and serve to hold the same in position.

The slide A of the honey-chamber is provided with a recess, I, to receive the overlapping edge of the piece B of the adjacent frame, a, and is provided with a single staple, C, which is adapted to fit within the slot g of the adjacent frame in locking said frame to the side of the chamber.

The side A² of the chamber is provided with a flange or extension, A³, adapted to overlap the adjacent frame, a', and the outer face of said flange is provided with a recess, g, to receive the staple upon said section, and the parts are secured together in the manner described for securing together the adjacent frames.

By the above construction the frames may be quickly and easily taken apart or put together when desired, the securing means being simple and inexpensive and not liable to get out of order.

What I claim as new is—

1. The combination, with the end frame having a slot, as described, of the adjoining frame provided with a hook, as shown, and the keeper having a cam surface engaging said hook, substantially as described.

2. The combination, with the frames formed with staples or hooks, of the end frames formed with a flange having a slot and channel, as de-

scribed, and the keeper formed with cam-surface f engaging said hook and seated in said channel, substantially as described.

3. The combination, with the side A^2 of the 5 surplus-honey chamber having a flange formed with channel d and slot b , of the sections a' , provided with staples or hooks, as shown, the plates B , formed with slots and channels, and the keepers formed of wire bent to form the

cam-surface f , substantially as and for the purpose specified.

In testimony whereof I affix my signature in presence of two witnesses.

THOMAS M. COBB.

Witnesses:

CHAS. E. HOGADORN,
W. J. FORTIER.
